UNITED STATES PATENT OFFICE.

GEORGE J. FRITZ, OF ST. LOUIS, MISSOURI.

DESIGN FOR A FRAME FOR IRONING-MACHINES.

SPECIFICATION forming part of Design No. 16,788, dated July 13, 1886.

Application filed May 5, 1886. Serial No. 201,246. Term of patent 7 years.

To all whom it may concern:

Be it known that I, GEORGE J. FRITZ, a citizen of the United States, residing at St. Louis, in the State of Missouri, have invented and produced a new and original Design for Ironing-Machine Frames, of which the following is a specification, reference being had to the accompanying drawing, forming part thereof.

The drawing is a perspective view of my newly-designed ironing-machine frame provided with an ironing device.

My design consists of a frame formed with end pieces having straight sloping sides A, inverted approximately V-shaped top A'', and cross pieces or bars A'.

A'' are bars extending from end piece to end piece.

I claim as my invention—

The improved design for ironing-machine frames, substantially as herein shown and described, which consists of end pieces formed with straight sloping sides A, inverted approximately V-shaped top A'', and cross-bars A' and bars A'', extending from end piece to end piece.

GEO. J. FRITZ.

In presence of—

GEO. H. KNIGHT,
EDW. S. KNIGHT.
